UNITED STATES PATENT OFFICE

FRIEDRICH ADLER, OF HAMBURG, GERMANY

PRINTING TEXTILE FABRICS

Application filed January 22, 1929, Serial No. 334,284, and in Germany April 13, 1928.

A process is known for printing fabrics with wax, wax substitutes, paraffin or similar resisting means, according to a pattern. Such a process consists primarily in placing 5 the fabric to be printed upon a fixed or solid layer of wax, and printing it right through with a heated metal stamp which bears the pattern.

The layer of wax may be constructed as a 10 cylinder and may co-operate with a roller-shaped printing forme.

This process has been further improved by employing, instead of the fixed layer of wax, a fabric of any convenient length, which is 15 saturated with a resist. These two known processes furnish the basis for carrying out the printing of fabrics with a pattern, either by manual labour or mechanically.

The present invention relates to a device 20 by which the mechanical process is arranged in a particularly simple and rational manner. Practical experiments have shown that as compared with the best manual process, the mechanical process, which can be carried out 25 with the apparatus according to the present invention, yields at least twenty times the output, without the valuable qualities of hand-wax printing being in any way diminished.

30 The apparatus according to the present invention is illustrated in the accompanying drawings, wherein

Fig. 1 is a diagrammatic representation of the printing apparatus as a whole, and

35 Fig. 2 represents on a larger scale the particular wax spreader employed with this apparatus.

Figure 3 is a longitudinal section through the bundle of laminated felt and the corrugated sheet-metal boxes of the wax spreader, and

Figure 4 shows the laminated felt when the supply of wax is throttled.

The printing process for which the apparatus according to the present invention serves is carried out in the following manner:—

The fabric to be printed upon, together with the so-called resist web, that is to say, together with a web of fabric saturated with 50 a resist such as wax or the like, passes around

a printing cylinder. This printing cylinder is heated from within, and has printing forms in relief on its external periphery, which heat the wax of the resist web through the web of fabric, and consequently produce 55 wax impressions upon the web of fabric in accordance with the design thereof.

In order to enable different forms to be employed in a progressive working operation, a plurality of printing cylinders are 60 used according to the invention, which are arranged in a revolver-like manner, and can accordingly be easily interchanged at the working position.

In Figure 1 are shown three printing cylinders d , d^1 and d^2 , which are mounted upon a revolver D , and by means of the latter can be brought into the upper working position in succession.

The printing cylinders d , d^1 and d^2 are 70 heated by steam which is supplied through a live steam pipe 1 to one end of the hollow arbor of the revolver D , to the other end of which is connected a waste pipe 2, rotary packings being provided at each end of the 75 arbor in the well-known manner. The steam is passed from the hollow arbor of the revolver to the cylinders d , d^1 , d^2 and the condensed water returned thereto by means of pipes 21, 22, 23, 24, 25, 26 in open communication with the interior of the arbor and connected to the ends of the respective cylinders, rotary packings being also provided at ends of the cylinders for the said pipes.

Upon a roller a is wound the fabric b to be 85 printed. The fabric passes over a guide roller c , around a heated printing cylinder d , over a roller g , and is wound up on a roller j . Synchronously with the web of fabric to be printed there runs an endless web e , which 90 is saturated with the resist, and which is hereinafter referred to as the resist web. The latter is guided by a roller c^1 to the roller c^2 , then runs around the printing cylinder d along with the web b for at least half the periphery thereof, and is then deflected by rollers c^3 and f and runs past heated tubes F^1 , F^2 , F^3 , and through a melting trough K .

In association with this melting trough the resist web passes under a wax spreader 100

L, the method of operation of which will be hereinafter described, and the object of which is to spread upon the web *e* a uniform layer of wax or other resist. Along an ice box *m*, or alternatively by water-cooled rollers, the wax is cooled, whereby the regeneration process of the resist web is terminated.

In particular, it may be advantageous, in order to enhance the uniformity in the contact of the web *b* to be printed and the resist web *e* with the pattern roller *d*, to employ special auxiliary applying means travelling with the resist and fabric webs. Such an auxiliary means may for example consist of an endless band, which accompanies the fabric and resist webs in the working direction and presses both the webs against the printing roller *d*. A construction for this purpose is shown in Figure 1.

20 A compressing means, consisting of an endless band *z* running over rollers *c*², *c*³ and *c*⁴, presses the resist web *e* and the web of fabric *b* against the printing cylinder *d*. A roller *c*⁴ is slidably and resiliently supported in a 25 casing or guide *V*, and regulates the tensions or pressure of the band *z*. The rollers *c*, *c*², *c*³ and *g* are also supported in slide blocks *x* and *x*¹. The compression blocks and the slide blocks are located in a framework *y*, 30 which is let into a standard *y*¹ in such a manner as to be slidable in a vertical direction. Two toothed racks enable the slide blocks *x* and *x*¹ to be displaced to right and left in a known manner and to compress the spring bolts *y*², which hold the framework *y* firmly and lock it in the standard *y*² during the printing operation. As soon as the springs of these bolts are compressed, counterweights *w*¹ and *w*² act upon the framework, which is 35 now unlocked, and raise it. The space thereby left vacant enables the three printing cylinders *d*, *d*¹, and *d*², which are arranged in a revolver-like manner, to rotate, these cylinders being for the purpose of permitting of 40 continuous working with different pattern rollers. It is now possible for example, while the printing cylinder *d* is in the working position, to change the cylinder *d*¹, which has quitted the working position, for a fresh cylinder, without interrupting the printing process.

Such a printing process proceeds in the following manner:—

The printing cylinder is provided on its 55 cylindrical surface with patterns in relief, and is heated in any convenient manner. The pressure applying means, consisting for instance of a calico band, produces during the rotation an intensive contact of the raised patterns with the fabric and the resist web. The raised patterns on the roller *d* therefore cause the liquefied resist of the resist web *e* to be absorbed by the web of fabric *b*. The web *b* thus printed through, may pass directly 60 to a dye bath or the like instead of pass-

ing to a winding roller *j*, as shown in Fig. 1. In order however to protect the wound fabric and the wax printing from friction and sticking, an accompanying web *o* may be rolled up with them as an intervening layer.

The wax spreader *L* is illustrated on a larger scale in Figure 2 and consists of a trough *p*, the wax content of which is passed on to the resist web by laminated felt strip *n*. In order to keep the wax liquid, the trough *p* is provided with a steam pipe coil *q*. Moreover between the layers of felt *n* are located sheet-metal boxes *r*, in which electrical heating units are lodged, as shown in Figure 3. A double-armed lever *s*, which is 70 rotatable about a pivot *s*¹, and projects to the outside of the trough, so as to be capable of being actuated from the outside, acts upon a grating *t*. The closure of the grating *t* regulates the supply of wax by squeezing the 75 layers of felt and thus shutting off to a greater or less extent the path of the wax between the boxes *r*.

This regulating is effected in the following manner: The felt strips *n* are freely suspended from girders or carriers *n*¹, between boxes *r* and oval rollers *t*¹, which engage by pins *t*² in slots *t*³ in the grating *t*. When the grating *t* and the rollers *t*¹ are in the position shown in Fig. 2, the laminations *n* hang down 90 freely and permit a maximum quantity of wax to flow down them. If the grating *t* is moved in the direction of the arrow towards the left by actuating the lever *s*, the grating, owing to the rods *t*⁴, rotates the oval rollers *t*¹, which consequently, as shown in 95 Figure 4, compress the felt laminations located between them. The path of the wax is thereby diminished in size.

The boxes, as will be seen from the diagrammatic view in Figure 3, are constructed as corrugated sheet-metal boxes, so that passages remain for the wax between the laminations and the boxes.

The wax spreader is so adjusted that the 105 layers of felt only touch quite lightly the resist web which glides past beneath it, and provide for a completely uniform spreading of the wax from above. This one-sided impregnation of the web has the great advantage of 110 economizing the wax and accelerating the cooling thereof, this being further assisted by the ice cooler *m* or other similar cooling means such as cold water cylinders and the like. A sheet-metal closure *u*, which is 120 slidably underneath the bundle of layers *n* in guides *u*¹, is intended, before or shortly after starting, to prevent the influx of wax completely, and to take up the wax residues which have already passed the grid closure *t* 125 before it comes into operation. Steam pipes *W* may also advantageously be passed through the interior of the trough *p*.

In order that the resist web may remain in reliable contact with the felt laminations, a 130

supporting block B is provided underneath them and above the edge of the trough K. The trough K itself is for the purpose of melting the wax which is still located upon the resist strip, in order that the fresh coating of wax may be uniformly formed.

This purpose is served by steam pipes k^2 and a stripper k^1 . The trough K is moreover of such length that overflowing wax from the wax spreader L is caught thereby.

10 What I claim is:—

1. Apparatus for printing webs of fabric according to a pattern, comprising a printing cylinder, a printing forme in relief on the convex surface of the printing cylinder, means for heating the cylinder, means for passing the web to be printed upon uniformly around at least half the periphery of the printing cylinder, a resist web, and means for passing 15 the resist web around the printing cylinder along with the web of fabric.

2. Apparatus for printing webs of fabric according to a pattern, comprising a printing cylinder, a printing forme in relief on the convex surface of the printing cylinder, means for heating the cylinder, means for passing the web to be printed upon uniformly around at least half the periphery of the printing cylinder, a resist web in the form 20 of an endless band, and means for passing the resist web around the printing cylinder along with the web of fabric.

3. Apparatus for printing webs of fabric according to a pattern, comprising a printing cylinder, a printing forme in relief on the convex surface of the printing cylinder, means for heating the cylinder, means for passing the web to be printed upon uniformly around at least half the periphery of the printing cylinder, a resist web in the form of an endless band, a melting trough for wax, a wax spreader, a cooling device, means for passing the resist web around the printing cylinder along with the web of fabric, and 35 means for passing the resist web, after the printing operation, through the melting trough, under the wax spreader, and over the cooling device.

4. Apparatus for printing webs of fabric according to a pattern, comprising a printing cylinder, a printing forme in relief on the convex surface of the printing cylinder, means for heating the cylinder, means for passing the web to be printed upon uniformly around 40 at least half the periphery of the printing cylinder, a resist web, means for passing the resist web around the printing cylinder along with the web of fabric, and auxiliary applying means for supplementarily and uniformly pressing the resist web and the web of fabric against the printing cylinder.

5. Apparatus for printing webs of fabric according to a pattern, comprising a printing cylinder, a printing forme in relief on the convex surface of the printing cylinder,

means for heating the cylinder, means for passing the web to be printed upon uniformly around at least half the periphery of the printing cylinder, a resist web, means for passing the resist web around the printing cylinder along with the web of fabric, and resiliently held calico bands guided in the working direction for supplementarily and uniformly pressing the resist web and the web of fabric against the printing cylinder.

6. Apparatus for printing webs of fabric according to a pattern, comprising a printing cylinder, a printing forme in relief on the convex surface of the printing cylinder, means for heating the cylinder, means for passing the web to be printed upon uniformly around part of the periphery of the printing cylinder, a resist web in the form of an endless band, a melting trough for wax, a wax spreader, a cooling device, means for passing the resist web around the printing cylinder along with the web of fabric, means for passing the resist web, after the printing operation, through the melting trough, under the wax spreader, and over the cooling device, and auxiliary applying means comprising resiliently held calico bands guided uniformly in the working direction for supplementarily and uniformly pressing the resist web and the web of fabric against the printing cylinder.

7. Apparatus for printing webs of fabric according to a pattern, comprising a revolvable cylinder holder, a plurality of printing cylinders exchangeably mounted thereon, the cylinder holder being adapted to enable any one of the cylinders mounted thereon to be moved into the printing position at will, printing formes bearing different patterns in relief on the convex surfaces of the various printing cylinders, cylinder heating means, means for passing the web to be printed upon uniformly around at least half the periphery of the printing cylinder that is in the operative position, a resist web, and means for passing the resist web around the printing cylinder along with the web of fabric.

8. Apparatus for printing webs of fabric according to a pattern, comprising a revolvable cylinder holder, a plurality of printing cylinders exchangeably mounted thereon, the cylinder holder being adapted to enable any one of the cylinders mounted thereon to be moved into the printing position at will, printing formes bearing different patterns in relief on the convex surfaces of the various printing cylinders, cylinder heating means, rollers for guiding the web to be printed upon uniformly around at least half the periphery of the printing cylinder that is in the operative position, a resist web, rollers for guiding the resist web around the printing cylinder along with the web of fabric, and movable supporting means for the said guiding rollers, adapted to enable the guid-

ing rollers to be moved out of the way when the cylinder holder is to be rotated to change the pattern.

9. Apparatus for printing webs of fabric
5 according to a pattern, comprising a revolu-
ble cylinder holder, a plurality of printing
cylinders exchangeably mounted thereon, the
cylinder holder being adapted to enable any
one of the cylinders mounted thereon to be
10 moved into the printing position at will,
printing formes bearing different patterns
in relief on the convex surfaces of the vari-
ous printing cylinders, cylinder heating
means, rollers for guiding the web to be
15 printed upon uniformly round at least half
the periphery of the printing cylinder that
is in the operative position, a resist web, roll-
ers for guiding the resist web around the
printing cylinder along with the web of
20 fabric, auxiliary applying means such as re-
siliently held calico bands guided uniformly
in the working direction for supplementary
and uniformly pressing the resist web and
the web of fabric against the printing cylin-
25 der, rollers for guiding the said auxiliary
applying means, and movable supporting
means for the said guiding rollers, adapted
to enable the guiding rollers to be moved out
of the way when the cylinder holder is to be
30 rotated to change the pattern.

In testimony whereof I have signed my
name to this specification.

FRIEDRICH ADLER.
